UNITED STATES PATENT OFFICE.

HERMANN WITTMANN, OF MANITOWOC, WISCONSIN.

TOY.

SPECIFICATION forming part of Letters Patent No. 724,226, dated March 31, 1903.

Application filed December 16, 1902. Serial No. 135,366. (No model.)

To all whom it may concern:

Be it known that I, HERMANN WITTMANN, a citizen of the United States, and a resident of Manitowoc, in the county of Manitowoc and 5 State of Wisconsin, have invented a new and Improved Toy, of which the following is a full, clear, and exact description.

This invention relates to improvements in toys, the object being to provide a toy so arranged that by casting it upon a table or floor 10 it may be caused to assume various forms or shapes indicating various objects and also serve for elementary lessons in arithmetic, thus not only providing amusement, but having 15 educational features.

I will describe a toy embodying my invention and then point out the novel features in the appended claim.

Reference is to be had to the accompanying 20 drawings, forming a part of this specification, in which similar characters of reference indicate corresponding parts in all the figures.

Figure 1 is a plan view of a toy embodying 25 my invention, showing one of the forms that may be assumed. Fig. 2 is a plan view showing another form. Fig. 3 is a section on the line $x-x$ of Fig. 1, and Figs. 4, 5, and 6 show other forms.

The toy comprises a ring 1 of suitable material—such, for instance, as metal wire. Mounted to swing on the ring independently 30 one of another are substantially V-shaped members 2. The ends of these members are provided with eyes 3, through which the ring extends.

In throwing the toy upon a table or the

like, as before stated, it may be caused to assume various shapes—such, for instance, as a comet, as indicated in Figs. 1 and 4, a full moon, as indicated in Fig. 2, a star, as illustrated by Fig. 5, and a disk or the like, as shown in Fig. 6.

As an educational device the members extending outward may be added to the members extending inward, or one set of members 45 may be subtracted from the other set of members, thus not only providing amusement to a child, but serving somewhat as a kindergarten instrument.

In practice I will provide with the toy a 50 chart suitably colored to indicate the various forms to be assumed by the toy.

The toy is especially applicable to kindergarten work, as a child may by means of the toy form at least forty-nine symmetrical 55 shapes, and thus give the child an idea of shape and form.

Having thus described my invention, I claim as new and desire to secure by Letters Patent—

A toy comprising a ring, and a plurality of members mounted to swing thereon independently one of another, the said members being of uniform size and adapted to swing into the ring.

In testimony whereof I have signed my name to this specification in the presence of two subscribing witnesses.

HERMANN WITTMANN.
